VALVE

Roy Wilson Hays, Rockford, Ill.

Application November 29, 1946, Serial No. 712,765

2 Claims. (Cl. 284—14)

1

This invention relates to automatic closing valves for admitting air or other gas into a bag or chamber.

One object is to provide a novel valve of the above character which may be made cheaply from sheet metal stampings.

Another object is to provide a valve which is adapted to receive and interlock detachably with a filling nozzle so as to be held open thereby and permit filling of the associated bag with a gas at a relatively low pressure.

Still another object is to form the valve parts with cooperating clamping elements for securing the valve to a bag.

Other objects and advantages of the invention will become apparent from the following detailed description taken in connection with the accompanying drawings, in which

Figure 1 is a longitudinal cross sectional view of the improved valve and a portion of a supporting bag, the section being taken on the line 1—1 of Fig. 3.

Fig. 2 is a longitudinal sectional view taken along the line 2—2 of Fig. 3.

Fig. 3 is a plan view taken along the line 3—3 of Fig. 1.

Fig. 4 is an enlarged fragmentary sectional view taken along the line 4—4 of Fig. 3.

Fig. 5 is a view similar to Fig. 2 showing a modification.

The improved valve is shown in the drawings adapted for use in closing one end of a clothes bag 10, or the like, after the latter has been filled with a gaseous insecticide delivery, preferably at low pressure, through a pipe or nozzle 11. The valve includes a generally cylindrical shell or tube 12 having an outturned, preferably right angular flange 13 with one end adapted to bear against the external surface of the bag around an opening 14 therein.

The other end of the shell is shaped to receive and cooperate with the nozzle 11 to form a connection for holding the two together with the valve held open. In the form shown in Figs. 1 to 3, the nozzle fits snugly in the shell and is held securely therein by interengagable bayonet elements engaged by inserting the nozzle to move outwardly projecting pins 16 thereon into the bottoms of recesses 15 in the shell and then turning the nozzle within the shell to carry the pins into the laterally extending parts 17 of the recesses.

A relatively shallow cup 18 having a flat bottom 19 and a generally cylindrical side wall is pressed upside down into the other end of the

2

shell 12. In this operation, an outturned flange 20 around the lip of the cup is moved toward the shell flange 13, the bag margin thus being clamped firmly between two flanges to form a gastight seal around the bag opening. Preferably the flanges are corrugated as shown to provide more effective clamping.

The valve proper is formed by a flat disk 21 co-operating with holes 22 punched out of the cup bottom 19 and arranged in an annular series. Herein the edges of the metal defining the holes are depressed slightly in the punching operation to define seats 23 of narrow radial width so that the holes may be closed tightly when a disk 21, which is composed of rubber or another relatively pliable material, is pressed lightly against the seats. The disk 21 which is slightly smaller in diameter than the cup 18 is attached as by adhesive to a metal supporting disk 24 riveted or otherwise secured at its center to one end of a stem 25 which projects slidably through a hole in the cup bottom. A coiled compression spring 26 encircling the stem above the cup bears against a crossbar 27 riveted on the other end of the stem. Thus when the crossbar is released as shown in Fig. 1, the valve disk 21 is pressed against the seats 23 with sufficient force to form effective seals around the holes and thereby close the latter against the escape of gas from the bag.

30 The crossbar 27 is spaced from the open end of the shell so as to be engaged by the end of the nozzle 11 when the latter is inserted in the shell 12. Then in the further movement of the nozzle to carry the pin 16 into the bayonet recesses 15, 35 the valve disk 21 is moved away from the seats 23 to open all of the valve holes as shown in Fig. 2, the end portion of the nozzle then fitting tightly in the cylindrical part of the shell. As the nozzle is turned in the shell to complete the bayonet 40 connection, it becomes locked in the shell against withdrawal, and serves to hold the valve open without further attention by the operator. The valve is closed automatically by the spring 26 as the nozzle is disconnected and withdrawn from the shell.

In the modified form shown in Fig. 5, the nozzle 11, when inserted in the shell 12, engages the latter with a relatively tight friction fit which serves to hold the valve open while the nozzle 50 remains inserted. To this end, the open end of the shell is tapered a few degrees, the internal wall 29 diverging inwardly from an end flange 28. The nozzle is formed with a complementary external taper of such size that the end of the 55 nozzle engages and depresses the crossbar 24

before it becomes wedged in the shell as shown in Fig. 5. The wedging action thus produced is sufficient to hold the valve open, while at the same time permitting removal of the nozzle by a twisting motion.

It will be observed that nearly all of the parts of the improved valve are simple sheet metal stampings that may be assembled readily to enable the valve to be constructed at very low cost. At the same time the valve is opened, held open, and closed automatically as an incident to the operation of filling the bag 18 from the nozzle 11.

I claim as my invention:

1. A valve of the character described, comprising a cylindrical shell having an outturned flange at one end, a cup having a valve hole in its closed end and an outturned flange around its open end cooperating with said first flange to form a clamp, the defining edge of said hole being depressed out of the plane of said cup and, the closed end portion of said cup being pressed into said shell to close said clamp, a disk within said cup axially spaced inwardly and cooperating with said pressed out edge to form a valve, a stem carrying said disk at one end and projecting slidably through the closed end of said cup, means on the other end of said shell forming one element of a detachable connection and adapted for engagement with a nozzle when the latter is telescoping with said shell, and means on said stem engageable with the nozzle and operable to hold said

disk away from said hole while said connection is maintained.

2. A valve of the character described, comprising a shell having an outturned flange at one end, the other end being adapted to receive a filling nozzle, a cup having a valve hole in its closed end and an outturned flange around its open end cooperating with said first flange to form a clamp, the closed end portion of said cup being pressed into said shell to close said clamp, a disk within said cup axially spaced inwardly from the cup flange and cooperating with said hole to form a valve, a stem carrying said disk at one end and projecting slidably through the closed end of said cup, an abutment on said stem spaced from said cup, and a spring encircling said stem and acting between said cup and said abutment to urge said disk toward said valve hole.

ROY WILSON HAYS.
